UNITED STATES PATENT OFFICE.

HUGO J. BACHMAN, OF DENVER, COLORADO.

INTERNAL-COMBUSTION ENGINE.

1,155,699.

Specification of Letters Patent. Patented Oct. 5, 1915.

Application filed November 12, 1913. Serial No. 800,569.

To all whom it may concern:

Be it known that I, HUGO J. BACHMAN, a citizen of the United States, residing at Denver, in the county of Denver and State 5 of Colorado, have invented certain new and useful Improvements in Internal-Combustion Engines, of which the following is a specification.

This invention relates to internal combustion engines and more particularly to improvements in engines of the type shown in my application for patent, Serial Number 744,687, filed in the United States Patent Office, January 28, 1913.

15 Its object resides in providing a novel method of jacketing the exhaust valve of the engine whereby to effectively insulate the contacting surfaces thereof from the detrimental influence of the heat radiating from 20 the gases of combustion which when the engine runs at high speed, flow in a substantially continuous stream through the valve.

In accordance with the present invention I provide one or more air spaces which are 25 in continual communication with the atmosphere and through which air is automatically circulated by the suction creating effect of the stream of gases flowing into the interior of the valve through a bell-mouthed 30 nozzle at its extremity.

An embodiment of my invention is illustrated in the accompanying drawings in the various views of which like parts are similarly designated and in which—

35 Figure 1 represents a longitudinal section taken through an engine to which my invention is applied, with the piston and valves shown in elevation, Fig. 2, an enlarged sectional view of the exhaust valve 40 of the engine, and adjacent parts of the working cylinder and valve cylinder of the same, Fig. 3, a section similar to that shown in Fig. 2 with the exhaust valve in the position in which it uncovers the exhaust 45 port of the cylinder for the escape of gases of combustion therefrom, and Fig. 4, a transverse section taken along the line 4—4, Fig. 3.

50 Referring more specifically to the drawings, the reference numeral 2 designates the working cylinder of the engine which is open at one of its ends and in which a trunk-piston 3 is fitted for reciprocation.

55 Formed integrally and axially parallel with the cylinder 2, is the valve-cylinder 4 in which an intake valve 5 and an exhaust

valve 6 are slidably fitted in tandem relation to each other, the two cylinders being spaced from each other and surrounded by an integral mantle to provide a jacket which 60 completely incloses the same.

The two cylinders are connected by an intake port 7 and an exhaust port 8 through which the motive fluid is admitted into and discharged from the compression end of the 65 working cylinder, and the valve cylinder is furthermore provided with a port 9 which connects with the carburetor or other source of combustible mixture.

The piston 3 is by means of a connecting 70 rod 12, operatively connected with the crank arm of a crank shaft 13 which through the instrumentality of a pair of gear wheels 14 and 15 proportioned at a ratio of one to two, imparts its rotary motion at a reduced rate 75 of speed to a second shaft 16.

The rotary movement of the last-mentioned shaft is converted into independent reciprocating movements of the two valves 80 by means of eccentrics 17 which are placed at right angles to each other and whose rods are articulately connected with the valve rods.

The rod of the intake valve is bored longitudinally for the sliding movement of the 85 rod of the other valve within the same, both rods being guided in their reciprocating movement in suitable boxes, one of which has been shown in section in Fig. 1.

In the operation of the engine the explosive mixture introduced into the valve cylinder through the port 9 is at the proper point in the cycle of movements of the operative parts of the engine, conveyed to the intake port 7 of the working cylinder through a 90 passage in the intake valve which not forming part of the present invention has not been shown in detail in the drawings.

Securely mounted upon the circumferential flanged, open exhaust end of the valve 100 cylinder is a hollow cylindrical element 18 which forms an extension of the said cylinder and which provides a connection between the latter and the exhaust pipe 19 which is rigidly secured upon its outer extremity.

The exhaust valve which like the other valve is of the piston type, consists of a cylindrical shell which adjacent its closed inner end has a port 20 which when the valve 110 is at or near the end of its outward stroke, registers with the exhaust port 8 for the es-

cape of the gases of combustion from the cylinder 2.

An axially, inwardly extending, bell-mouthed nozzle 21 formed integrally with the cylindrical shell of the valve 6 provides a tapering passage through which the gases admitted through the port 20 are conducted in their course to the exhaust conduit.

The element 18, the body portion of which is disposed between the valve cylinder and the exhaust port includes a hollow cylindrical core 22 of reduced diameter which being formed integral with the said body portion, extends from the inner surface thereof, axially within the hollow exhaust valve in concentric and spaced relation to its circumferential wall. The lower end of the core has a slightly reduced mouth adapted to receive the end of the nozzle 21 on the valve when the latter reaches the end of its outward stroke at which the opening 20 is in register with the exhaust port 8 of the working cylinder as shown in Fig. 3.

A mantle 23 integrally connected with the core by means of spacing lugs 24, provides a jacket around the same, the said mantle being open at both its ends and formed at its lower extremity to permit of the free passage of the valve nozzle as it enters the mouth of the core.

The element 18 is furthermore provided with a plurality of openings 25 which being formed between the point of its connection with the valve cylinder and the point at which the outer end of its core joins its interior surface, connect the annular space between the inner surface of the valve shell and the mantle of the core, as well as the jacket formed by said mantle with the atmosphere.

The valve 6 has in a plane with its port 20, a number of openings 26 through which the gases flow into the balance chamber 10 for the purpose of equalizing their pressure upon the inner and outer surfaces of the valve to prevent its binding in the cylinder, and packing rings 27 are applied in exterior recesses of the valve shell for the usual purpose.

When in the cycle of operations of the engine the exhaust valve is moved outwardly for the escape of the gases of combustion after the charge of explosive mixture has been ignited in the compression end of the working cylinder and the piston is thereby driven outwardly to effect a rotary movement of the crank shaft, the opening 20 having been brought in register with the exhaust port 8, causes the gases of combustion developed in the working cylinder to enter the nozzle 21 which forcibly ejects them into the mouth of the core through which they pass to the exhaust conduit.

The rapid flow of the gases through the contracted end of the nozzle creates a partial

vacuum which draws air through the openings 25 into the two jackets formed between the inner surface of the valve shell and the core, to be discharged therefrom through the spaces between the nozzle and the mouths of the mantle and the core, into the interior of the latter.

From the foregoing it will be seen that the flow of gases between the exhaust port of the cylinder 2 and the exhaust pipe 19 causes a continuous circulatory movement of air through the valve to cool its shell and prevent its being affected by the intense heat of the gases which in the ordinary operation of the engine flow through its interior in a substantially continuous stream.

Having thus described my invention what I claim and desire to secure by Letters Patent is:

1. In an internal combustion engine, a working cylinder and a valve chamber connected by a port, a hollow valve movably mounted in the said chamber, and having an inwardly directed nozzle and an opening for establishing communication between the said nozzle and the said port, and an element providing a passage for gases ejected from the said nozzle through the interior of the valve, in spaced relation to the wall of the same, the said space connecting with the atmosphere and with the mouth of said passage adjacent said nozzle.

2. In an internal combustion engine, a working cylinder and a valve chamber connected by a port, a hollow valve movably mounted in the said chamber, and having an inwardly directed nozzle and an opening for establishing communication between the said nozzle and the said port, and an element providing a jacketed passage for gases ejected from the said nozzle, through the interior of the valve in spaced relation to the wall of the same, the said space connecting with the atmosphere and with the mouth of said passage adjacent said nozzle.

3. In an internal combustion engine, a working cylinder and a valve chamber connected by a port, a hollow valve movably mounted in the said chamber, and having an inwardly directed nozzle and an opening for establishing communication between the said nozzle and the said port, an element providing a passage for gases ejected from the said nozzle, through the interior of the valve in spaced relation to the wall of the same, and including a mantle forming an open-ended jacket around said passage, both the said space and the said jacket connecting with the atmosphere and with the mouth of said passage adjacent said nozzle.

4. In an internal combustion engine, a working cylinder and a valve-cylinder connected by a port, a hollow valve movably fitted in said valve cylinder and having an inwardly directed nozzle and an opening

for establishing communication between the said nozzle and the said port, and an element including an open-ended hollow core extending within the valve in spaced relation to the interior surface of the same, and means for connecting said space with the atmosphere, the said core being adapted to receive at its inner end, the gases ejected through said nozzle and the said space being connected with the same end of the core for the admission of air thereinto.

5 5. In an internal combustion engine, a working cylinder and a valve-cylinder connected by a port, a hollow valve movably fitted in said valve cylinder and having an inwardly directed nozzle and an opening for establishing communication between the said nozzle and the said port, and an element including an open-ended jacketed hollow core 10 extending within the valve in spaced relation to the interior surface of the same, and means for connecting said space with the atmosphere, the said core being adapted to receive at its inner end, the gases ejected through said nozzle and the said space being connected with the same end of the core for the admission of air thereinto.

15 6. In an internal combustion engine, a working cylinder and a valve-cylinder connected by a port, a hollow valve movably fitted in said valve cylinder and having an inwardly directed nozzle and an opening for establishing communication between the said nozzle and the said port, and an element including an open-ended hollow core 20 extending within the valve in spaced relation to the interior surface of the same, a mantle forming an open-ended jacket around said core, and means for connecting said space and said jacket with the atmosphere, the said core being adapted to receive at its inner end, the gases ejected through said nozzle, and the said space and the said jacket being both connected with 25 the same end of the core for the admission of air thereinto.

25 7. In an internal combustion engine, a working cylinder and a valve cylinder connected by a port, a hollow valve movably fitted in said valve cylinder and having an

opening adapted to register with said port for the discharge of gases from the working cylinder, and a passage extending through said valve in spaced relation to its interior surface, means for directing gases 55 passing through the valve-opening into the inner end of said passage, the space around the said passage being in connection with the atmosphere and with the said end of the passage.

60 8. In an internal combustion engine, a cylinder having an exhaust port, an exhaust conduit, a connection between said port and said conduit, having an air-inlet, a hollow valve controlling the flow of gases through 65 the said connection, and means in said connection, for causing by the flow of gases through the same, a current of air to enter the connection through its said inlet and pass along the interior surface of the valve, 70 to a determinate point of discharge.

9. In an internal combustion engine, a cylinder having an exhaust port, an exhaust conduit, a connection between said port and said conduit, having an air-inlet, a hollow 75 valve controlling the flow of gases through the said connection, and means in said connection, for causing by the flow of gases through the same, a current of air to enter the connection through its said inlet and 80 pass along the interior surface of the valve into the exhaust-conduit.

10. In an internal combustion engine, a cylinder having an exhaust port, an exhaust conduit, a connection between said port and 85 said conduit, having an air-inlet in direct communication with the atmosphere, a valve controlling the flow of gases through said connection, and means in said connection for causing, by a flow of gases through the 90 same, a current of air to enter the connection through its said inlet and pass along a surface of the valve to a determinate point of discharge.

In testimony whereof I have affixed my 95 signature in presence of two witnesses.
